Filed July 5, 1966, Ser. No. 2,916

Term of patent 7 years

(Cl. D56—4)

FIG. 1

FIG. 2

FIG. 3.

FIG. 4

FIG. 1 is a front, top and right side perspective view of a television receiver, showing my new design with the carrying handle and telescoping antenna folded down;

FIG. 2 is a rear, bottom and left side perspective view;

FIG. 3 is a front elevational view, to an enlarged scale; and

FIG. 4 is a right side elevational view thereof, to a reduced scale, with the carrying handle and telescopic antenna in extended position.

The dominant features of my new design are shown in solid lines in the drawing.

The fenestrated grille at the bottom of the front face is continuous within the boundaries indicated.

I claim:

The ornamental design for a television receiver, substantially as shown and described.
